(57) **CLAIM**

The ornamental design for a tire as shown and described.

DESCRIPTION

FIG. 1 is a perspective view of a tire, showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top plan thereof;

FIG. 7 is a bottom plan thereof; and,

FIG. 8 is a partial enlargement of the front view.

Broken lines in FIG. 2 used for demarcation of enlarged portions of the tire form no part of the claim.
